SANDAL OR SIMILAR ARTICLE

Walter Braun, Los Angeles, Calif., assignor to Cobblers Incorporated, Los Angeles, Calif., a corporation of California

Application November 23, 1951, Serial No. 17,508

Term of patent 7 years

(Cl. D7—7)

To all whom it may concern:

Be it known that I, Walter Braun, a citizen of the United States, residing at Los Angeles, in the county of Los Angeles, State of California, have invented a new, original, and ornamental Design for a Sandal or Similar Article, of which the following is a specification, reference being had to the accompanying drawing, forming a part thereof.

Figure 1 is a perspective view of a sandal or similar article showing my new design.

I claim:

The ornamental design for a sandal or similar article, as shown.

WALTER BRAUN.
